UNITED STATES PATENT OFFICE

THOMAS SILVER, OF NEW YORK, N. Y., ASSIGNOR TO ORVILLE D. LOVELL,
OF SAME PLACE.

MECHANICAL LAMP.

SPECIFICATION forming part of Letters Patent No. 329,600, dated November 3, 1885.

Application filed November 15, 1884. Serial No. 147,998. (No model.)

To all whom it may concern.

Be it known that I, THOMAS SILVER, of the city and county of New York, in the State of New York, have invented a new and useful 5 Improvement in Mechanical Lamps, of which the following is a specification.

My invention relates to that class of lamps known as "mechanical lamps," in which the flame is supplied with air from a current produced by a rotary fan driven by clock-work or equivalent mechanism within the stand of the lamp.

The nature of the invention consists in the novel method of communicating motion to and regulating the speed of the fan. Heretofore a 15 spur-wheel engaging a worm upon the upright fan-shaft has commonly been used for this purpose. In my own patent, No. 287,334, dated October 23, 1883, I have employed a step form 20 of contact or anti-friction wheels. My present invention, however, more especially consists in the combination, with the fan and the motor employed to drive it, of a plain driving friction-wheel secured upon a horizontal shaft 25 and engaging with its periphery the face of a rotary plain friction-disk upon the upright fan-shaft and transmitting motion to said disk and the shaft, the said driving friction-wheel being adjustable in a direction parallel with 30 the axis of its shaft, and thus capable of being brought nearer to or farther from the center of the disk on the fan-shaft to provide for varying the speed of the fan, as may be required to diminish or increase the supply of 35 air to the lamp-burner, which cannot be done with the step-formed anti-friction wheels heretofore employed to transmit motion to the fan without changing some of the wheels of the gearing.

With a view to compensate for the unavoidable variation in the tension of the spring employed as the motor of the clock-work or mechanism for driving the fan, and thereby to equalize or preserve uniformity of the speed 45 of the fan, and so produce a uniform supply of air to the burner, my invention also consists in the combination, with the said mechanism and the said friction-wheel and friction-disk, of automatic means of moving the said friction-wheel toward or from the center of the

disk as the tension of the spring is increased or diminished.

The invention further consists in certain details of construction, hereinafter described and claimed.

Figure 1 is a vertical sectional view of the column or pillar of a lamp, showing also, partly in section and partly in elevation, a blowing apparatus constructed according to my invention. Fig. 2 is a vertical sectional view of 60 the same blowing apparatus, taken at right angles to Fig. 1. Fig. 3 is a plan view illustrating the friction-wheel, its shaft, and the frame that carries it.

Similar letters of reference denote corresponding parts in all the figures.

A designates the hollow column adapted to form the stand of a lamp and a casing for the fan and its driving mechanism.

As neither the reservoir nor burner forms a 70 part of my invention, they are not here shown.

B designates the frame-work, which supports and furnishes bearings for the train of wheels D, driven by a spring, C.

G designates the fan, carried by the upright 75 shaft H', which is journaled at h and h'. Upon this shaft is fixed the plain flat friction-disk H, and upon the horizontal shaft E, which is the last shaft of the train, is mounted the plain friction-wheel F, which, as will be presently more fully described, transmits motion 80 from the spring and train to the fan. The fan G is arranged in a case, g, near the top of the casing or column A. The bottom of this fan-case has an opening, g', in its central part, to 85 admit air to the fan. Motion is transmitted from the shaft E to the fan-shaft H' by the periphery of the friction-wheel F, running in contact with the under face of the friction-disk H. This wheel and disk may be made 90 of hard rubber or any other suitable material. It is well understood that the effective working force of such a spring will naturally diminish as the tension produced by winding is expended. This diminution of effective force, 95 if it were not compensated for, would produce a constant decrease in the speed of the fan. This inequality may be obviated by causing the periphery of the friction-wheel F to engage the friction-disk H successively in parts 100

at different distances from its center during the action of the driving-spring. This may be accomplished automatically in various ways. In the example given, to enable such a compensation to be effected the shaft E is journaled in a horizontally-movable frame, I, which is provided with three gudgeons, i^1 i^2 , fitted to slide in a direction parallel with the shaft E in suitable openings in the main frame 5 B. This frame is kept pressed against a lever, C', on one side by a spring, K, attached to the main frame B on the opposite side. This lever C' is fulcrumed to the main frame at c^2 , and its upper end is fitted with a screw, e' , 10 which bears against the frame I. The lower end of the said lever is notched to engage a flange on a nut, c, which is fitted to a screw-thread, C², on the back end of the spring-winding arbor C'. A fixed pin, b, secured in 15 the framing B and projecting into a notch in the nut c, prevents it from turning with the screw, but permits it to move longitudinally thereon. The screw C² has its thread running in the opposite direction to that in 20 which the winding-arbor is turned to wind up the spring—that is to say, the arbor being turned to the right, the screw has a left-hand thread. As the spring C is wound up, the nut c moves outward on the screw C², carrying with it the lower end of the lever C'. This causes the upper end of the lever to move 25 the frame I, and with it the shaft E and friction-wheel F, in a direction to carry the periphery of the said wheel toward the center 30 of the friction-disk H. When the spring is wound up and its tension is greatest, this periphery will have arrived at its position nearest to the center of the disk, where it will encounter the greatest resistance in driving the 35 fan, on account of its having only the minimum of leverage on the disk H. As the spring in unwinding turns the winding-arbor, the screw-thread C² on the latter moves the nut c inward 40 toward the driving-spring, and the nut so moving carries with it the lower end of the lever C', and causes the upper end thereof to move outward. The spring K, now pressing 45

against the side of the frame I, which is farthest from the lever, causes the said frame to follow the motion of the upper end of the lever. The 50 frame I carries with it the friction-wheel F, so that the periphery of the latter is constantly moving away from its center as the driving-spring unwinds, and constantly meeting with less and less resistance in driving the fan, and 55 thus the constant decrease of effective power in the unwinding-spring is compensated to produce a uniform speed of the fan during the action of the driving-spring.

What I claim as my invention, and desire 60 to secure by Letters Patent, is—

1. In a mechanical lamp, the combination, with the rotary fan and the train of mechanism for obtaining the power for driving the same, of a friction-disk on the shaft of the fan, and 65 a friction-wheel on the last shaft of the train, working in contact with said disk and adjustable toward and from the center thereof for the purpose of varying the speed of the fan, substantially as herein described. 70

2. In a mechanical lamp, the combination, with the rotary fan and spring-actuated mechanism for rotating it, of a friction-disk on the fan-shaft and a friction-wheel for transmitting motion from the said mechanism to said disk, and an automatic device actuated by said mechanism for moving the said wheel toward and from the center of said disk, substantially 75 as herein described.

3. The combination, with the rotary fan-shaft H', the friction-disk H upon said shaft, and a train of spring-actuated wheels comprising a shaft, E, carrying a friction-wheel, F, engaging with said disk, of the movable frame I, carrying said shaft E, the screw C², moving 85 with the spring-winding arbor, the nut c on said screw, and the lever C' between said nut and said movable frame, substantially as and for the purpose herein described. 80

THOS. SILVER.
